A. SCHREINER.
LADDER RUNG.
APPLICATION FILED SEPT. 9, 1916.

1,250,520.

Patented Dec. 18, 1917.

UNITED STATES PATENT OFFICE.

ALBERT SCHREINER, OF DENVER, COLORADO, ASSIGNOR TO THE SCHREINER LADDER MANUFACTURING COMPANY, A CORPORATION OF COLORADO.

LADDER-RUNG.

1,250,520.

Specification of Letters Patent.

Patented Dec. 18, 1917.

Application filed September 9, 1916. Serial No. 119,202.

To all whom it may concern:

Be it known that I, ALBERT SCHREINER, a citizen of the United States, residing at Denver, in the county of Denver and State of Colorado, have invented certain new and useful Improvements in Ladder-Rungs, of which the following is a specification.

This invention relates to improvements in ladder rungs and its principal object resides in providing a metal rung of simple construction the ends of which are adapted to be forced into the wood of the side rails of a ladder so as to anchor the rung firmly in place without weakening the rails between which it is applied.

Another object of my invention is to provide in connection with rungs of the improved construction, means for securing the ladder rails against spreading, and still another object is to adapt the improved rungs for use on step ladders as well as on ordinary ladders.

With the above and other objects in view, all of which will fully appear in the course of the following description, my invention comprises the constructions shown in the accompanying drawings in the various views of which like parts are similarly designated, and in which—

30 Figure 1 represents an elevation of a ladder equipped with my improved rungs.

Fig. 2, an enlarged cross section of the ladder showing the rung in elevation,

35 Fig. 3, a sectional elevation of an end of the rung before it is placed on the ladder,

Fig. 4, a side elevation of a portion of a ladder rail to which the rung shown in Fig. 3, is attached,

40 Fig. 5, a section taken along the line 5—5, Fig. 4,

Fig. 6, a plan view of the end of a rung adapted for use on step ladders,

Fig. 7, an end view of the rung shown in Fig. 6, and

45 Fig. 8, a sectional view of the rung shown in Figs. 6 and 7, in place on the side rail of a step ladder.

Referring to the drawings by numerical characters of reference, 2 designates the side rails of a ladder, and 3 the rungs connecting the same.

My improved rung consists of a piece of sheet metal bent to form a bar of channel section. One side, 4, of the bar is preferably

made wider than the other side, 5, of the same, mainly for the purpose of reducing the cost of production and to avoid weakening the ladder rail to which the rung is applied.

The face or cross plate 6 of the rung is incised at its ends to provide two tapering prongs 7 of which the end portions of the side plates 4 and 5 form part, and, intermediate of said prongs, a tapering prong 8 of reduced length which is bent to slant downwardly as shown in Fig. 3.

To apply a rung thus formed, to the ladder rails, its ends are forced into the wood of the rails between which it is placed, by means of a suitably constructed press.

The wedge-shaped outer prongs 7 upon entering the wood, retain their original form while the downwardly bent prong 8 is bent still further, as shown in Fig. 4, and thus anchors the rung against longitudinal displacement.

After the rung has been driven into the side rails, until the edges of its cross plate between the prongs, engage the inner surfaces thereof, it is secured by means of nails 9 which are driven into the rails and through the side plates of the rung as is best shown in Fig. 5.

After the nails are driven home, metal straps 10 are secured to the rails to cover the heads of the nails and thereby hold them in place.

To still further strengthen the structure and prevent spreading of the side rails of the ladder, diagonal braces 12 are secured between the rails and the under side of some of the rungs as shown in Fig. 1, it being in most instances sufficient to apply these braces to every other rung of a ladder of ordinary length.

A rung for use on step ladders as shown in Figs. 6 to 8, is substantially similar in form to the rung hereinabove described, except that its cross plate is wider and that two or more prongs are formed between the outer prongs at its ends.

The side members of the step ladder rung are bent at an acute angle to its cross plate to correspond to the slant of the side rails when the latter is in its working position.

In securing the rung between the rails of a step-ladder, one of its side members is placed in engagement with the edges of the side

rails at the front of the ladder, while the ends of the other side member and the prongs formed at the ends of its cross member are driven into the wood as before.

5. It will be readily seen from the foregoing description that in a ladder of the improved construction herein described, the rungs are very strong and durable and that the side rails unweakened by holes as in ladders of
10 ordinary construction, are firmly secured against spreading.

The end prongs of the rungs being composed partially of the side flanges of the channel bar and partially of portions of the
15 web or face of the bar adjoining said flanges, are particularly adapted to withstand downward pressure and thereby hold the rungs against displacement by the user's weight.

Having thus described my invention in
20 the best form at present known to me I desire it understood that modifications other than those mentioned in the foregoing description, may be resorted to within the spirit of my invention as set forth in the
25 following claims.

I claim:

1. A ladder-rung comprising a bar having at each end, two outer prongs and between the same a prong slanting from the
30 frame of said bar, said prongs being adapted to be forced into the wood of side rails of a ladder between which the rung is placed.

2. A ladder-rung comprising a bar having at each end two outer prongs and between the same a shorter prong slanting from the plane of said bar, said prongs being adapted to be forced into the wood of side rails of a ladder between which the rung is placed.

3. A ladder-rung comprising a bar having at each end two outer prongs and between the same, a shorter, downwardly slanting prong, said prongs being adapted to be forced into the wood of said rails of a ladder between which the rung is placed.

4. A ladder comprising a pair of side wooden rails, and rungs composed of metal channel-bars having at their ends integral
50 prongs slanting from the planes of the re-

spective bars which are forced into the substance of said rails.

5. A ladder-rung comprising a bar having at each end a prong extending substantially parallel with the plane of the bar, and a prong slanting from said plane, said prongs being adapted to penetrate wooden side rails of a ladder, between which the rung is placed.

6. A ladder rung comprising a channel bar having at each end three outwardly projecting integral prongs formed by incisions of its cross member and adapted to penetrate wooden side-bars of a ladder, between which the rung is placed, the middle prong at each end of the channel bar slanting from the plane of the same.

7. A ladder rung comprising a bar having at its opposite ends, integral prongs which slant divergently from the plane of the bar and are adapted to penetrate wooden side-rails of a ladder, between which the rung is placed.

8. A ladder comprising wooden side-rails, and metal rungs having at their ends outwardly projecting prongs which are forced into the side rails and slant divergently downwardly from the planes of the rungs.

9. A ladder comprising a pair of wooden side-rails, and metal rungs made of channel-bars of a width less than that of said side-rails, and having at their ends outwardly projecting prongs which are driven into the rails, one of the side members of each of said channel-bars lying flat against corresponding edges of the rails.

10. A ladder rung consisting of a channel-bar having in the ends of its web or face, incisions the side edges of which extend at a distance from the side flanges of the channel bar leaving end prongs formed partly by portions of the web and partly by the side flanges of the bar.

In testimony whereof I have affixed my signature in presence of two witnesses.

ALBERT SCHREINER.
